CLAIM

The ornamental design for a wine glass, as shown and described.

DESCRIPTION

FIG. 1 is a perspective view of a wine glass of the present design;

FIG. 2 is a front view of the wine glass of FIG. 1;

FIG. 3 is a rear view of the wine glass of FIG. 1;

FIG. 4 is a left side view of the wine glass of FIG. 1;

FIG. 5 is a right side view of the wine glass of FIG. 1;

FIG. 6 is a top view of the wine glass of FIG. 1; and,

FIG. 7 is a bottom view of the wine glass of FIG. 1.

The broken lines shown in the drawings are for illustrative purposes only and form no part of the claimed design. The dash-dot-dash broken lines define the bounds of the claimed design and form no part thereof.

1 Claim, 4 Drawing Sheets
